COIL

Nathan Sterenbuch, New York, and Martin Saffer, Glendale, N. Y.

Application March 12, 1946, Serial No. 653,927

7 Claims. (Cl. 175—21)

(Granted under the act of March 3, 1883, as amended April 30, 1928; 370 O. G. 757)

1

This invention relates to a magnetizing coil and more particularly to a magnetizing coil that is divided and hinged and is of the type used in the "Magnaflux" or "Magnaglo" methods of detecting flaws in metals.

By these methods, metal objects are coated with particles having magnetic properties either in powder form or suspended in a liquid and the objects subsequently magnetized, the patterns of the particles indicating the presence of flaws in the material.

Heretofore, a solid type coil was used to magnetize the articles to be tested, this type coil often causing great inconvenience when the objects to be tested were of large size and not movable readily. The split-type coil herein disclosed may be used readily on any size object without the necessity of the object being removed from its supports.

The object of this invention is to provide a coil for magnetizing objects, which coil is of a separable construction, can be placed about the object simply and expeditiously, and can be used without moving the object from its supports.

Further objects and advantages of this invention, as well as the arrangement and operation, will be apparent from the following description and claims in connection with the accompanying drawings, in which

Fig. 1 is a front elevational view of the magnetizing coil;

Fig. 2 is a side elevational view of the magnetizing coil; and

Fig. 3 is a front elevational view of the jack and plug connectors.

Front and rear circular frames are designated by the numeral 10. Frames 10 are divided into semicircular halves or sections 11 along the vertical diametric plane, as viewed in Fig. 1. Base members 12 are provided at the bottom of each of the frame sections 11. The upper portions of each pair of frame sections 11 are connected by a hinge 30 attached to the frame sections 11 by means of screws 31. Between the frames 10 and coaxial therewith is a tubular core 13 divided into two sections 14 along the same diametric plane which divides the frames 10. Core sections 14 are attached to frame sections 11 in any suitable manner. Extending between frame sections 10 and directly below tubular sections 14 are blocks 15 and 16 secured to the frame sections 11 by means of screws 21. Within the blocks 15 are located jacks 18. Within the blocks 16 are located complementary plugs 19.

Helically wound about the tubular core 13 is

2

a coil 17, each of the convolutions of the coil 17 being interrupted by a plug 19 and jack 18 combination. The ends of the coil 17 protrude through the frame 10 and terminate in lugs 22, which are adapted to receive connectors from an electrical source. Trunk-type latches 20 are provided for each pair of frame sections 11 to lock them together.

In the operation of the device, the latches 20 are opened, the frame sections 11 are swung apart about their hinges 30 and the device is placed about the object to be magnetized. The frame sections 11 are then swung together and locked by means of latches 20. The electrical terminals 15 are connected to the lugs 22 on the ends of coil 17 and the object is thereupon magnetized for the testing operation. The device may be slid along the object to be tested to magnetize various portions thereof or removed readily and placed about other objects to be tested.

It is understood that various modifications and changes may be made in this invention without departing from the spirit and scope thereof as set forth in the appended claims.

25 The invention described herein may be manufactured and used by or for the Government of the United States of America for governmental purposes without the payment of any royalties thereon or therefor.

30 We claim:

1. A coil comprising a first generally circular frame, a second generally circular frame, said frames having semicircular components, hinges connecting the said components of each circular frame, a generally tubular core between said frames, said core being divided into equal parts and extending between said frames, blocks between said frames below the parts of said tubular core, a helically wound coil on said core, plugs in one of said blocks, jacks on the other of said blocks, each of the convolutions of said coil being severed, the severed ends of each of said convolutions terminating in one of said jacks and plugs, and the ends of said coil protruding through said frames.

2. A coil comprising a generally circular front frame, and a generally circular rear frame, each of said frames comprising two generally semicircular parts and being divided along the same diametric plane, the upper portions of each pair of semicircular parts being hinged together, a tubular core between said frames, said core having two parts and being divided in the same diametric plane as said frames, blocks between said frames, each of said blocks being located below

said core and being adjacent to each other, a series of plugs in one of said blocks, a series of jacks in the other of said blocks, a helically wound coil about said core, each of the convolutions of said coil being interrupted by a plug and jack, the ends of said coil protruding through said frames, and means to lock said frames together.

3. A coil comprising a pair of bifurcated frames, a hinge linking the components of each frame proximate an end of such bifurcation, a core mounted between said frames, said core comprising components secured to corresponding components of each of said frames, a plurality of plugs mounted between corresponding components of said frames opposite said hinge, a plurality of jacks secured to the other corresponding components of each of said frames and adapted to be inserted in corresponding plugs, a plurality of coils wound on said core, each coil terminating in one of said plugs and one of said jacks to form a helix, and means to connect the ends of said helix to an electrical circuit.

4. A coil comprising a pair of bifurcated frames, a hinge linking the components of each frame proximate an end of such bifurcation, a core mounted between said frames, said core comprising components secured to corresponding components of each of said frames, a plurality of plugs mounted between corresponding components of said frames opposite said hinge, a plurality of jacks secured to the other corresponding components of each of said frames and adapted to be inserted in corresponding plugs, a plurality of coils wound on said core, each coil terminating in one of said plugs and one of said jacks to form a helix, means to connect the ends of said helix to an electrical circuit, and means to lock together the components of said frames.

5. A coil comprising a pair of bifurcated frames, means to link together the components of each frame proximate an end of such bifurcation for relative rotation, a generally tubular core mounted between said frames, said core comprising a pair of semi-cylindrical components secured to corresponding components of each of said frames, a first block secured to corresponding components of each of said frames opposite said hinge and carrying a plurality of plugs, a second block secured to the other corresponding components of each of said frames and carrying a plurality of jacks adapted to be inserted in corresponding plugs, a plurality of coils wound on said core, each coil terminating in one of said plugs and one of said jacks to form a helix, and means extending through said

in one of said plugs and one of said jacks to form a helix, and means to connect the ends of said helix to an electrical circuit.

6. A coil comprising a pair of bifurcated frames, means to link together the components of each frame proximate an end of such bifurcation for relative rotation, a generally tubular core mounted between said frames, said core comprising a pair of semi-cylindrical components secured to corresponding components of each of said frames, a first block secured to corresponding components of each of said frames opposite said hinge and carrying a plurality of plugs, a second block secured to the other corresponding components of each of said frames and carrying a plurality of jacks adapted to be inserted in corresponding plugs, a plurality of coils wound on said core, each coil terminating in one of said plugs and one of said jacks to form a helix, means to connect the ends of said helix to an electrical circuit, and means to lock together the components of said frames.

7. A coil comprising a pair of bifurcated frames, means to link together the components of each frame proximate an end of such bifurcation for relative rotation, a generally tubular core mounted between said frames, said core comprising a pair of semi-cylindrical components secured to corresponding components of each of said frames, a first block secured to corresponding components of each of said frames opposite said hinge and carrying a plurality of plugs, a second block secured to the other corresponding components of each of said frames and carrying a plurality of jacks adapted to be inserted in corresponding plugs, a plurality of coils wound on said core, each coil terminating in one of said plugs and one of said jacks to form a helix, and means extending through said frames adapted to connect the ends of said helix to an electrical circuit.
